UNITED STATES PATENT OFFICE.

GEORGE A. BADGER AND WILBER FOWLER LAKIN, OF QUINCY, ASSIGNEES
TO JOHN H. LAKIN, OF BOSTON, MASSACHUSETTS.

CASH AND PARCEL CARRIER.

SPECIFICATION forming part of Letters Patent No. 314,558, dated March 31, 1885.

Application filed May 24, 1884. (No model.)

To all whom it may concern:

Be it known that we, GEORGE A. BADGER and WILBER F. LAKIN, both of Quincy, in the county of Norfolk and State of Massachusetts, have invented certain Improvements in Cash and Parcel Carriers, of which the following is a full, clear, and exact description, reference being had to the accompanying drawings, making part of this specification, in which—

10. Figure I represents one end of a wire track in an elevated position, with a carrier having our improvements applied thereto. Fig. II is an elevation of the carrier detached, with our improved locking, cushioning, and starting devices in their normal position. Fig. III is a plan of the top of the same. Fig. IV is an inner end elevation of the guide and track support, with an adjustable stop having the carrier-releasing device attached thereto. 20 Fig. V is a perspective view of our adjustable stop detached. Fig. VI is a longitudinal central section through a carrier adapted to hold a memorandum book or tablet of records of sales and cash received therefor. Fig. VII is a 25 transverse section on the line *x x* of Fig. VI.

Our present invention consists in a carrier having a device secured thereto which performs the double function of cushioning or reducing the force of the concussion of the carrier on its arrival at the bottom of the incline, and also of starting the carrier down the track when unlocked from its elevated position.

Our invention also consists in a device secured to a carrier for locking the same to the track-support at the depressed end, in order that it may be raised therewith when the track is to be inclined in the opposite direction, the carrier, when elevated and ready to return by its gravity, being liberated from the track-support by the said locking device being brought into contact with the releasing device located above it.

Our invention also consists in an adjustable stop for limiting the upward movement of the track-support, the adjustable feature enabling said stop to be conveniently applied to tracks of different lengths requiring different angles of inclination.

Our invention furthermore consists in a 50 clasp, also secured to the end of the carrier,

for embracing the lower end of the track-support, in order that no lateral movement of the carrier may occur when locked and raised to its elevated position.

Our invention also consists in a carrier adapted to receive a memorandum book or tablet containing records of sales and cash received therefor, an adjustable spring-actuated support for the book or tablet being employed, to be hereinafter described and claimed. 55

To enable others skilled in the art to understand and use our invention, we will proceed to describe the manner in which we have carried it out.

In the said drawings, A represents a cash 65 or parcel carrier having a pair of wheels, *a*, resting on a wire track, B, the ends of which are secured to supports C, which are caused to slide on vertical guides D by operating the track-inclining cords *b*, each of said track-supports being held, when elevated, by a pivoted latch, *c*, having a notch, *d*, for the reception of a projection, *e*, on the track-support when brought in line therewith. At two of the diagonal corners of the carrier are formed 70 projections *f*, to each of which is pivoted a bent lever, *h*, the upper end of which has pivoted thereto a long arm, *i*, the outer end of which is provided with an incline and a notch forming a hook, *k*. The lower outer end 75 of the lever *h* terminates in a cylindrical projection or roll, *l*, extending out at right angles therewith. The inner end of the hooked arm is secured to a spiral spring, *m*, by means of an interposed screw, *n*, which adjusts the tension of the same, the spring being secured to the carrier at *p*. The lever *h*, with its cylindrical projection or roll *l*, serves to cushion 80 or reduce the force of the concussion of the carrier when it reaches the depressed end of 85 the track, and also serves to start the carrier when elevated and ready to return down the incline in the opposite direction. The hook *k* performs the office of locking the carrier to the track-support at the depressed end, in 90 order that it may be elevated therewith when the incline is changed. The locking device *k* and the cushioning and starting device are represented in their normal positions in Figs. 95 II and III.

As tracks of different lengths require different degrees of inclination in order to afford a convenient means of limiting the elevation of the track-supports, we provide the upright 5 guide D with an adjustable stop, G, which may be readily slid up or down, and be clamped, when adjusted to the required height, by means of a set-screw, r; and to prevent the swinging of the lower end of the latch e into the path 10 of and obstructing the track-support when being raised we provide the adjustable stop with a pin or projection, s, for the upper outer end of the latch to abut against, which thus limits the vibration of its lower end.

15 Secured to the inner end of the adjustable stop G, and extending down below it into the path of the carrier-locking device k, is a plate, t, under which the inclined outer end of said device is carried when the track-support, with 20 the carrier, has been elevated to the top of the incline, the plate t serving to release the carrier and allow of its return to the lower end of the track.

At the bottom of each end of the carrier is 25 secured a bifurcated spring-plate, u, which embraces the opposite sides of the lower end of the track-support, and maintains the carrier steadily in its upright position when locked and while being raised.

30 When the carrier A arrives at the bottom of the incline, the roll l at the lower outer end of the lever h comes into contact with the lower end of the track-support, and the spring m is caused to yield, thus reducing the force 35 of the impact of the carrier as desired, simultaneous with which the incline of the hook k rides under a pin, v, projecting from the rear of the track-support, and the hook is engaged therewith, thus locking the carrier 40 thereto.

When the carrier is elevated with the track-support by pulling down on the track-inclining cord b, the projection e of the support is brought in line with and catches into the notch 45 of the pivoted latch e, which thus holds the track-support in its elevated position until a continued pull on the elevating-cord raises it a slight distance farther, when the incline of the hooked arm is depressed by contact with 50 the under side of the tripping-plate t and the hook k is released, thus leaving the carrier free to descend the incline, the liberation of the spring m causing the roll l to exert a forcible pressure against and away from the track-support and starting the carrier on its return 55 downward as desired.

In Figs. VI and VII is shown a carrier adapted to hold a memorandum book or tablet. Near the top of the outside of each end of the carrier is pivoted an arm, H, to the inside of the lower end of which is secured a V-shaped block, I, occupying a position under the bottom of the carrier, the carrier being hollow for the reception of the book K. Each arm H 65 is connected with a spring, w, which keeps it

vertical in its normal position. The two blocks I form supports for the bottom of the book, and are connected by a bent rod, L.

To locate the book in the carrier the hand holding it is pressed against the rod L, so as 70 to swing the supports to one side of the open bottom, when, after entering the book, the hand is withdrawn, and the arms H are vibrated by their springs, so as to return the supports I under the bottom of the ends of 75 the car, thus keeping the book in place as desired.

We claim—

1. As an improvement in cash or parcel carriers, the device, substantially as described, 80 secured thereto for locking the same to a track-support, in order that the carrier may be elevated therewith, in combination with means, substantially as described, for releasing the locking device when the carrier is ready to 85 descend the incline.

2. A cash or parcel carrier provided at one or both ends with a hook connected with a spring, in combination with means, substantially as described, for liberating the hook 90 when the carrier is at the elevated end of the track and ready to return to the depressed end thereof, substantially as described.

3. A cash or parcel carrier having secured thereto a device for cushioning the 95 same when it reaches the lower end of the track, and for starting the carrier from its elevated position down the track, as set forth.

4. A cash or parcel carrier having one or both of its ends provided with lever h, connected 100 with spring m, the latter being extended when the outer end of the lever comes in contact with the track-support or its guide, the retraction of the spring causing said end of the lever to exert a forcible pressure away from the track- 105 support or its guide, as set forth.

5. In combination with a cash or parcel carrier, a locking device and a cushioning and starting device having their movements controlled by a spring, for the purpose described. 110

6. A cash or parcel carrier having a clasp- 115 ing device secured thereto, in combination with the device, substantially as described, located at the end of the track, for the purpose specified.

7. A spring-clasp, u, secured to a cash or parcel carrier, in combination with a track-support or its guide, for the purpose described.

8. An adjustable stop, G, in combination 120 with a track-support, C, and its guide D, for limiting the upward movement of the track-support, for the purpose set forth.

9. An adjustable stop, G, having a pin, v, in combination with and for locking the carrier-hook k, as specified. 125

10. An adjustable stop, G, having a pin, v, and a plate, t, in combination with a carrier-hook, k, as and for the purposes designated.

11. In combination with the adjustable stop 130

G, the pin or projection *s*, for limiting the vibration of the notched latch *c*, substantially as and for the purpose explained.

12. A carrier having its lower end open 5 and provided with a spring-actuated device, which in its normal position is located under the carrier to form a support for a book contained therein, and which may be vibrated to one side to allow of the introduction and removal of the book, as described.

13. A hollow carrier having an open bottom, in combination with a pair of arms, *H*,

having blocks I secured to their lower ends, and connected with springs *w* at their upper ends, constructed to operate as and for the purpose set forth.

Witness our hands this 20th day of May, 1884.

GEORGE A. BADGER.
WILBER FOWLER LAKIN.
